UNITED STATES PATENT OFFICE.

FRANCIS FERDINAND STADIG, OF ST. FRANCIS, MAINE.

SLED ATTACHMENT FOR AUTOMOBILES.

1,070,301.

Specification of Letters Patent. Patented Aug. 12, 1913.

Application filed April 25, 1912. Serial No. 693,044.

To all whom it may concern:

Be it known that I, FRANCIS F. STADIG, a citizen of the United States, and residing at St. Francis, in the county of Aroostook and 5 State of Maine, have invented a new and Improved Sled Attachment for Automobiles, of which the following is a full, clear, and exact description.

My invention is especially designed to 10 provide a sled, and propelling mechanism therefor attachable to standard makes of automobiles without altering the car, other than to remove the wheels, whereby to convert the car into a practical motor sled.

15 Objects of my invention are to provide an attachment of the character referred to, comprising runners that sustain the weight of the car, and propelling mechanisms independent of the runners.

20 Further objects are to provide independent propelling mechanisms at each side of the car adapted to accommodate themselves to inequalities of the road, independently of each other; to provide a propelling mechanism 25 in which the traction will be automatically proportionate to the pull; and to provide propelling mechanism improved in various structural and functional respects.

The distinguishing features of my invention, and the important structural elements 30 characterizing the preferred embodiment illustrated as examples will be fully explained in the specific description herein-after to be given.

35 Reference is to be had to the accompanying drawings forming a part of this specification, in which similar characters of reference indicate corresponding parts in all the views.

40 Figure 1 is a side elevation of a sled attachment embodying my invention, and showing the same applied to an auto car having a counter-shaft with side chain drive; Fig. 2 is a plan view of the said attachment removed from the car; Fig. 3 is an enlarged detail side elevation of the rear runner and propelling mechanism; Fig. 4 is a vertical section taken on about the line 4-4 of Fig. 2; Fig. 5 is a cross section taken 45 on about the line 5-5 of Fig. 3; Fig. 6 is a detail cross sectional view of the sprocket chain and its traction blades, the section being taken on about the line 6-6 of Fig. 7; Fig. 7 is a detail side elevation of a portion 50 of the chain; Fig. 8 is a side elevation of the

rear sled and its propelling mechanism slightly modified to adapt the same to an auto having a rear axle drive; Fig. 9 is a plan view of the attachment shown in Fig. 8, including portions of the car; and Fig. 10 60 is a sectional elevation taken on about the line 10-10 of Fig. 9, the sprocket chain and wheels, and some other parts being omitted.

Referring particularly to the form of the invention shown in Figs. 1 to 7, the attachment comprises runners 10 having knees 11 hinged by any suitable form of clip or shackle 12 (Fig. 4) to a cross bar or rear axle 13 of the car, or to any equivalent bar adapted to replace the axle, the bar or axle 70 being held by the shackle or clip 14 to the rear springs 15 of the car, the arrangement being such that the weight of the car will be imposed upon the runners and be sustained by the latter. 75

The propelling attachment comprises thrust bars 16, 17, hung at their forward ends 18, 19, on the counter-shaft 20, or otherwise hung from any convenient member of the car. Each thrust bar desirably 80 is made up in the form of a frame consisting of side arms 21, 22, the respective side arms being united by cross bars 23 at their rear ends, and braced by diagonal braces 24, 25. The side arms 21 and 22 are given 85 any lateral deflection necessary to reach the proper point on the counter-shaft 20 and clear any of the frame members or operative parts. The thrust bars, designated generally by the numerals 16, 17, incline from the 90 counter-shaft 20 in a downward and rearward direction, and mount at their rear ends compensating levers 26, each comprising two spaced longitudinal members 27, fulcrumed on a stud shaft 28 that extends 95 horizontally from the outer side of each thrust bar 16, 17, the shaft being mounted in bearings 28a. The levers 26 carry on the rear ends of their arms 27, idler sprocket wheels 29, which may be secured to the ends 100 of the levers by brackets 30 on the respective arms 27, and at their forward ends said levers carry traction sprocket wheels 31. A sprocket chain 32 runs over the idler sprocket 29, over a drive sprocket wheel 33 on the 105 counter-shaft 20, and beneath the traction sprocket 31. The upper run of the chain being the working run and therefore tight, it will be obvious that the pulling strain 110 on the chain will tend to lift the idler

sprocket wheel 29, and therefore tend to lift the lever 26 bodily, but as the bodily lifting of the levers is resisted by the thrust bars 16, 17, the levers will tend to rock upward at their rear ends and downward at their front ends, so that the levers have a compensating action and the front traction wheel 31 will be forced downward in proportion to the pull exerted on the rear sprocket wheel 29 by the pull on the top run of the chain, and therefore the traction of the chain against snow and ice will be proportionate to the load. Furthermore, since the lower ends of the thrust bars are below the center of longitudinal strain thereon exerted through the pull on the rear sprocket wheel, any movement of the thrust bars must be downward, tending to force downward bodily, the whole traction unit, consisting of the thrust bars, levers, idler sprocket 29, traction sprocket 31, and the appurtenances hereinafter described carried thereby, and the sprocket chain, the downward bodily movement of the unit thus contributing to increase the traction in proportion to the "load," or the power exerted to drive the vehicle forward.

Because of the rocking movement of the levers in their described compensating action, and the consequent change of the relation between the sprocket wheels 29 and 31, I provide an equalizing device so as to maintain the same distance around the sprockets when the levers rock up and down in passing over an uneven road. The equalizing device comprises a sliding bearing 34 for the shaft 35 of the traction sprocket 31, said bearing being carried on a longitudinal bar 36 provided at its ends with hangers 37, whereby to permit the shaft 35 and its sprocket wheel 31 to shift longitudinally along the lever. The sliding of the bearing frame 36 is controlled by a shifting diagonal tie rod 38, pivoted at its lower end on the shaft 35 of the traction sprocket 31, and pivoted at its rear upper end, as at 39, to the upper end of a standard 40, which is secured by its foot or lower end 41 in any suitable manner to the lower rear end of the thrust bar 16 or 17, it being understood that there are compensating devices as described, for the propelling attachment at each side of the car. The diagonal rod 38 of the equalizing device is provided with a turn-buckle 38^a, to adjust its length and therefore to adjust the distance between the sprocket wheels 29, 31; also there is, preferably, a diagonal brace 40^a between the side arm 21 of the thrust bar and the standard 40.

Between the idler sprocket 29 and the traction sprocket 31, a guide shoe 42 is provided, beneath which the chain 32 runs and against the under side of which the chain rollers 43 contact. The shoe 42 is suspended

from the frame 36 by a hanger 44, so that said shoe will move forwardly and backwardly in response to the shifting movements of the said frame 36. The rear end of the shoe is guided by having a sliding connection with the foot 45 of a depending guide 46, the upper end of which is secured at any convenient point to a lever arm 27. Adjacent to the shoe 42, and in the front thereof, rollers 47 are provided, beneath which the chain runs, said rollers being mounted on a shaft 48 which is mounted in hangers 49, 50, carried by the ends of the sliding bearing frame 36.

As seen best in Figs. 6 and 7, the chain includes besides the rollers 43, links 51, 52, the outer links 51 having integral therewith, at the under side, blocks 53 running at the sides of the rollers 43, the said blocks having runner shoes 54 secured thereto as by bolts 55, said shoes having on their outer faces the transverse, perpendicular traction blades 56 to enter the ice or frozen snow. Desirably the shoes 54 have on their back faces transverse rounded beads 57 that seat in corresponding grooves 58 in the blocks 53.

The tractor-propelling units, as described, it will be observed, are freely suspended by the front swinging connection of the thrust bars 16, 17, and therefore the said units are gravitationally mounted. In connection with the tractor-units a manually controlled traction-increasing device is provided, including compression springs 60, to resist the bodily rising of the units. The springs 60 seat at their lower ends on the thrust cross bars 16, 17, preferably on the rear cross bars 23, from which bars retaining pins 61 rise, and extend upward beyond the upper ends of the springs, as seen best in Fig. 4. The upper ends of the springs abut against an arm 62 of a bell-crank lever 63, the upper end of which lever is connected with a rod 64 that extends forwardly and has any suitable connection with a hand lever 65, arranged within convenient reach of the operator. The connection between the end of the rod 64 may be through the medium of a crank arm 66 mounted on a shaft 67 on which the hand lever 65 is secured. Thus by throwing the lever 65 to exert a forward pull on the connecting rod 64, the bell-crank lever 62, 63, can be rocked to cause the arm 62 of the said lever to exert a downward pressure on the springs 60, and thus exert a downward pressure on the tractor-units to increase the traction of the chain against the snow. The crank lever 62, 63, is mounted on a cross bar or rod 63^a, which is supported from the axle or bar 13 by brackets 63^b, and in addition to the mentioned crank lever, there is a crank arm 62^a corresponding with the arm 62, and pressing by its outer end on a spring 60^a formed

and arranged similarly to the described spring 60, so that there is a compression spring on each of the thrust bars 16, 17.

As seen best in the plan view (Fig. 2) 5 the rear idler sprocket wheel 29 may be provided with a brake drum 29^b similar to the ordinary brake drum on standard auto cars, and in practice a brake band (not shown) may be employed in connection with 10 said drum, if desired. The brake illustrated in Fig. 4, comprises a vertical rocking dog 70, having a downwardly projecting hook 71 at its rear end, said dog being mounted intermediate its ends on a rock 15 shaft 72, journaled on bracket 73 mounted on the knee 11 of the runner, the forward end 74 of the dog being slotted as at 75, to receive a lateral engaging member 76 on a crank arm 77. There are two crank 20 arms 77, as shown in Fig. 2, mounted on a rock shaft 78, and integral with one of said arms and constituting therewith a bell crank, is a second crank arm 79 which engages with a connecting rod 79^a, extending forwardly and connected with a crank arm 80 which is mounted on a shaft 81 that carries the brake handle 82. Thus by throwing the handle 82, the dog 70 may be made to 25 dig into the road surface and thus brake the sled. The gear case of the car is indicated by the numeral 90 and the chassis by the numeral 91. The described brake is simply given here as an example and is not claimed in this application.

35 The front sleds 92 may be mounted in any suitable manner, an efficient plan being to hang the knees 93 from the front axle 94, by bearings 95 (Fig. 1) so that the usual steering devices employed will act to turn 40 the runners. The plan view (Fig. 2) indicates the usual steering rod 96, the arms 97, 98 of the steering knuckles, the coupling links 99 between the arms of the knuckles, and includes also a link 100, uniting the 45 opposite runners of the front sled at the front.

Desirably there are mounted housing members or side fenders for the sprocket mechanism, preferably formed in two sections 101, 102, overlapping and secured together adjustably by a bolt 103 and wing nut 104 or the like, the said fender sections being fastened respectively to a sliding part as the slide hanger 37, as by bolts 50 105 and wing nuts 106, and to the thrust bar on the lever, so that they may move relatively as the sprockets shift their positions.

As best shown in Fig. 3, the traction 60 chain 32 extends in a downwardly and rearwardly inclined direction from the drive sprocket 33 on the counter-shaft 20, to the teeth of the traction sprocket 31, the effect of which is to give the chain, and with it 65 the remainder of the propelling unit, a

tendency to ride over deep snow instead of a tendency to dig downward and embed the chain in the snow.

In the form of the invention illustrated in Figs. 8, 9 and 10, the described parts are essentially the same as in the construction shown in the other figures, there being a variation only to adapt the described propelling unit to a car having a rear axle drive. In Figs. 8 to 10 the rear axle 110 70 from which the auto wheels have been removed, has fitted to it a driving sprocket wheel 111, on which a drive chain 112 runs, said chain passing also over a sprocket wheel 20^a mounted on a shaft 114, which may have 75 suitable bearings on a bracket 115 attachable to the chassis 91^a. Shaft 114 has a second sprocket 20^b which corresponds with the drive sprocket 33 on the shaft 20. The propelling chain 32 runs over the sprocket 20^b, and over an idler sprocket 29^a corresponding with the sprocket 29. A traction sprocket 31^a of each unit is mounted on the shaft 35^a journaled in suitable boxes on slide frames 36^a, which are inserted against the under side of the lever arms 27^a, said slide frames being carried by diagonal rods 38^a of the sprocket equalizing device, and said diagonal rods being secured at their upper ends to the standard 40^b, corresponding with 80 the standard 40, and secured at their lower ends to the rear ends of the thrust bars 16^a, 17^a. The lever arms 27^a are mounted on stud shafts 28^b projecting laterally from the rear ends of the thrust bars 16^a, 17^a, the said stud shafts being journaled in 85 bearings 28^c secured to the under side of the said lever arms 27^a. Advantageously, diagonal braces 40^c extend from the standards 40^b to the thrust bars 16^a, 17^a. The traction chain 32 runs under rollers 47 between the sprockets 29^a, 31^a, as in the previous construction. In the form shown in 90 Figs. 8 to 10, however, the shoes 42^a are carried by hangers 44^a, which depend from slides 116, on which are mounted bearings 117 for the shaft 118 that carries the idler sprockets 29^a, and said slides 116 are connected by links 119 with arms 40^d, depending 95 from the stud shafts 28^b. The shoe 42^a has guided movement at its front end beneath the heel of a foot 120 formed on a hanger bracket 121, and an additional guide shoe 122 is provided in each unit at the lower end of a hanger 123 that depends 100 from the forward slide 36^a.

With the described construction, it will be seen that upon a tilting movement of the lever arms 27^a, in response to the draft strain exerted in an upward direction on 105 the sprocket 29^a through the traction chain 32, the lever arms 27^a are free to have a sliding movement relatively to the sliding frames 116 and 36^a, so that the same distance around the sprockets is preserved for 110 120 125 130

the chain notwithstanding the movement of the rocking lever.

The compression springs 60^a in the arrangement shown in Figs. 8 to 10, bear at their lower ends against the lateral arms 23^a on the rear ends of the suspended thrust bars 16^a, 17^a, and the crank arms 62^a exert a downward pressure on the upper ends of said springs in response to a pull on the rod 79^b, which is similar to the rod 79^a previously described. The crank arms 62^a are secured to a rock shaft 63^c, and one of said arms has a lever arm 62^d to constitute a bell-crank lever. Connection between the upper end of the arm 62^d and the operating rod 79^b may be effected by an intermediate lever 63^d, fulcrumed intermediate its ends on a bracket 63^e, which is secured to the shaft or bar 13^a which is shackled to springs 15^a and on which shaft or bar the runners 10 are hung. The lever arm 62^d of the bell crank has a stud 63^f that moves in a slot 63^g of the lever 63^d, in response to a pull on the rod 79^b.

It has been found that by giving the link 119 (Fig. 8) the right throw from its point of pivot on the arm 40^d, the sliding bearing frame 116 of the rear traction sprocket will be sufficient to equalize the distance around the three sprockets comprised in the traction unit, notwithstanding the rocking movement imparted to the track sprockets in passing over a rough road. It will be noted that the arm 40^d is in fixed relation to the thrust bar 16^a. Thus it will be seen that the equalizing may be performed by the sliding bearing of the rear sprocket alone, thereby making unnecessary the use of the sliding bearing of the front sprocket in this construction, should it be preferred to omit the front sliding bearing. If desired the sliding may be done by providing for the sliding of both front and rear sprocket bearings and thus adjusting or dividing up the throw between the two.

Having thus described my invention, I claim as new, and desire to secure by Letters Patent,—

1. A propelling attachment for vehicles, comprising a pivotally mounted thrust bar, a frame mounted on said thrust bar rearward of its pivot and having rocking movement relatively to the said thrust bar, and in addition having up and down bodily movement in response to the pivotal movement of the thrust bar, a propelling device mounted on said rocking frame and exerting its propelling force on the thrust bar through the medium of said rocking frame, and actuating means for the said device.

2. A propelling attachment for vehicles, consisting of a traction unit comprising a thrust bar, a traction chain, and means for automatically applying traction pressure on the chain according to the load, said means

comprising a member engaged by the chain and responding to the pull exerted on the chain by its actuating means, and a member exerting traction pressure on the chain and movable with the member engaged by the chain to press on the chain in proportion to the pull thereon.

3. A propelling attachment for vehicles, consisting of a traction unit comprising means for securing it to the vehicle, said means including a downwardly and rearwardly inclined bar, pivotally mounted near its front end to have an up and down rocking movement, a traction chain, actuating means for the chain, and means for automatically applying traction pressure on the chain according to the load, said means comprising a member engaged by the chain and responding to the pull exerted on the chain by its actuating means, and a member exerting traction pressure on the chain and movable with the member engaged by the chain to press on the chain in proportion to the pull thereon.

4. A propelling attachment for vehicles, comprising a thrust bar pivotally hung at a point forward of its rear end to permit up and down movement on its pivot, a vertically rocking lever fulcrumed on said thrust bar at a point rearward of the pivot of the thrust bar, a sprocket traction chain, an idler sprocket mounted on the lever in the rear of the fulcrum and engaged by the sprocket chain, the pull on said chain exerting a lifting action on the said idler sprocket and tending to rock the lever, a second sprocket wheel on the lever at a point forward of the fulcrum and exerting a traction pressure against the chain in proportion to the pull exerted on the idler sprocket by the chain.

5. A propelling attachment for vehicles, consisting of a tractor unit comprising a traction chain, actuating means for the chain including a drive sprocket, and means for automatically exerting traction pressure on the chain in proportion to the load, said means comprising a vertically rocking lever, a sprocket wheel mounted on an arm of said lever and engaged by the chain, and a traction sprocket movable with the other arm of the lever and exerting traction pressure on the chain.

6. A propelling attachment for vehicles, consisting of a tractor unit comprising a traction chain, actuating means for the chain including a drive sprocket, and means for automatically exerting traction pressure on the chain in proportion to the load, said means comprising a vertically rocking lever, a sprocket wheel mounted on an arm of said lever and engaged by the chain, and a traction sprocket movable with the other arm of the lever and exerting traction pressure on the chain, one of the

sprocket wheels on the lever having a sliding movement relatively to the lever.

7. A propelling attachment for vehicles, comprising a thrust bar, a means to secure it to the vehicle, a lever supported on the thrust bar to have a bodily vertical movement and fulcrumed intermediate its ends to have a rocking movement on the said fulcrum in addition to the bodily movement, a driven traction chain, and members on the respective arms of the mentioned lever, one of said members being engaged by said chain and responsive to the pull strain and the other of said members exerting traction pressure on the said chain.

8. In a tractor unit, the combination with a driven traction chain, of a lever, a support on which the lever is mounted to have a bodily vertical movement, means for connecting the said support with the vehicle, the lever being fulcrumed intermediate its ends to have rocking movement in addition to the bodily movement, and members on the respective arms of the lever, one of said members being engaged by said chain and responsive to the pull strain thereon and the other of said members exerting a traction pressure on the chain.

9. A propelling attachment for vehicles, consisting of a tractor unit comprising a bar adapted for connection with a vehicle to have up and down movement thereon, and traction devices carried by the bar, said traction devices including a driven traction chain, and a traction-increasing means for exerting pressure on the mentioned bar.

10. A propelling attachment for vehicles, consisting of a tractor unit comprising a bar adapted for connection with a vehicle, traction devices carried by the bar and exerting the propelling force thereof against the bar, said traction devices including a traction chain and actuating means therefor, and a manually-controlled traction-increasing means for exerting pressure on the bar.

11. A propelling attachment for vehicles, consisting of a tractor unit comprising a bar adapted for connection with a vehicle, traction devices carried by the bar and exerting the propelling force thereof against the bar, said traction devices including a traction chain and actuating means therefor, and a manually-controlled traction-increasing means for exerting pressure on the bar, the said traction-increasing means including a compression spring pressing on said bar, and arms adapted to bear against said springs and press the same.

12. A propelling attachment for vehicles, comprising a thrust bar having means at its front end to freely suspend it from a vehicle for vertically rocking movement, traction devices including a lever hung between its ends on the free end of the bar to

rock thereon, a traction chain, a drive sprocket for the chain, and sprocket wheels mounted on the opposite ends of the lever and engaged by the chain, the said traction devices exerting the propelling force thereof against the mentioned bar.

13. In a propelling attachment for vehicles, a lever fulcrumed intermediate its ends, means for mounting the lever on a vehicle, a driven sprocket chain, sprocket wheels mounted on the arms of the lever and engaging the chain, and guide shoes between the sprockets and beneath which the chain is guided, said shoes having longitudinal sliding movement on the lever.

14. In a propelling attachment for vehicles, a lever fulcrumed intermediate its ends, means for mounting the lever on a vehicle, a driven sprocket chain, sprocket wheels mounted on the arms of the lever and engaging the chain, guide shoes between the sprockets and beneath which the chain is guided, said shoes being movable longitudinally of the lever, and guide members carried by the lever and with which the shoes have forward and backward sliding engagement.

15. A propelling attachment for vehicles, consisting of a tractor unit comprising a rocking lever fulcrumed intermediate its ends, means for supporting the lever from a vehicle said means comprising a pivotally mounted bar on which the lever is mounted, a driven tractor chain, a sprocket on one end of the lever and on which the chain has a tendency to exert a lifting pressure, a sliding frame on the opposite end of the lever, means for supporting said sliding frame from the pivotally mounted bar, a traction sprocket mounted on said sliding frame, and guide devices supported on said frame and beneath which the lower run of the chain passes.

16. A propelling attachment for vehicles, consisting of a tractor unit, comprising a thrust bar adapted for attachment to a vehicle, a lever fulcrumed to rock on said thrust bar, a sprocket wheel carried by one end of said lever a slide on the other end of said lever, a sprocket wheel on said slide, and means for supporting said slide from the thrust bar independently of the lever.

17. In a tractor unit, the combination of sprocket wheels, a sprocket chain running around said wheels, and guiding means for the chain, said chain comprising links and rollers adapted to engage the sprocket wheels, said links carrying blocks provided with traction members, said blocks ranging at each side of the chain rollers, and the said guide devices including rollers contacting with the said blocks at the sides of the chain rollers.

18. In a traction unit, a driven sprocket chain, and a guiding means for the chain,

the said chain comprising links, and blocks supported by the links and provided with shoes having traction members on the under side, and the said guiding means including 5 a roller beneath which the shoe-carrying blocks of the chain have movement, and a shoe supported adjacent to the said roller.

19. A tractor unit comprising a driven traction chain, sprocket wheels engaging 10 said chain, one of said sprocket wheels being movable relatively to the other, and side fenders formed in sections movable relatively to each other in response to a relative movement of the mentioned sprocket wheels.

15 20. A propelling attachment for vehicles, comprising a thrust bar pivotally hung at a point forward of its rear end to permit up and down movement on its pivot, a vertically rocking lever fulcrumed on said thrust 20 bar at a point rearward of the pivot of the thrust bar, a sprocket traction chain, an

idler sprocket mounted on the lever in the rear of the fulcrum and engaged by the sprocket chain, the pull on said chain exerting a lifting action on the said idler and 25 tending to rock the lever, a second sprocket wheel on the lever at a point forward of the fulcrum and exerting a traction pressure against the chain in proportion to the pull exerted on the idler sprocket by the chain, 30 and guiding devices on the lever beneath which the chain has guided movement between the mentioned sprocket wheels carried by the said lever.

In testimony whereof I have signed my 35 name to this specification in the presence of two subscribing witnesses.

FRANCIS FERDINAND STADIG.
